CLAIM

The ornamental design for an electric air freshener, as shown and described.

DESCRIPTION

FIG. 1 is a front perspective view of an electric air freshener showing our new design;

FIG. 2 is a front view thereof;

FIG. 3 is a back view thereof;

FIG. 4 is a right side view thereof;

FIG. 5 is a left side view thereof;

FIG. 6 is a top view thereof, and,

FIG. 7 is a bottom view thereof.

The broken lines shown in the drawings are for illustrative purposes only and form no part of the claimed design.
